No. 852,549.

PATENTED MAY 7, 1907.

D. C. FISHER.

MASSAGE APPARATUS.

APPLICATION FILED JULY 3, 1905.

UNITED STATES PATENT OFFICE.

DANIEL C. FISHER, OF BOSTON, MASSACHUSETTS.

MASSAGE APPARATUS.

No. 852,549.

Specification of Letters Patent.

Patented May 7, 1907.

Application filed July 3, 1905. Serial No. 268,074.

To all whom it may concern:

Be it known that I, DANIEL C. FISHER, of Boston, in the county of Suffolk and State of Massachusetts, have invented a new and useful Massage Apparatus, of which the following is a specification.

The primary object of my invention is to provide an apparatus for treating the eyes and ears by a treatment similar to massage or similar to leaching of other parts of the body, although my apparatus may of course be used for other purposes where pressure or suction is to be applied intermittently. It has been found in the practice of treating the ears, eyes, etc., that either suction or pressure is at times desirable, and my apparatus is adapted to apply either to the body.

My invention consists essentially in the use of a source of fluid pressure, an instrument for application to the body of the patient, a conduit between them, and in providing in that conduit means to alternately connect the instrument with the source of pressure and with an atmosphere of lower pressure for the purpose of giving rapid impulses to the body of the patient without fear of danger to the part treated.

My invention consists also in the combination of a source of pressure; a three-way valve, and means to continuously operate the valve so that it will alternately connect a port leading to the object to be operated upon with an atmospheric port and a port connected with the source of pressure.

Another feature of my invention is a valve having a multiplicity of ports for the purpose of giving a multiplicity of impulses for each revolution of the valve shaft.

Other detailed features of my invention are described below:

In the drawings: Figure 1 is a sectional elevation of the preferred valve. Fig. 2 is a sectional elevation of the valve seat on line 2-2 of Fig. 1. Fig. 3 is a side elevation of the valve. Fig. 4 is a side elevation of the valve seat. Fig. 5 is a diagram showing the apparatus operating on the eye of the patient.

A is an eye cup connected by conduit B with the receptacle or valve casing D supported on base D'. Leading from receptacle D is conduit E having stop-cock e, gage e' and needle valve e''. Conduit E is connected with pressure or vacuum tank F having gage f and safety valve f' and having connection G with pressure or vacuum pump H. Re-

ceptacle D is spherical in form and comprises valve seat d which has ports d' extending through it from chamber d¹¹ to chamber d¹² and arranged in substantially circular form and which has ports d² arranged similarly to ports d' but alternating with them and extending through the valve seat to the atmosphere. Journaled in the receptacle is shaft d³ which has shoulder d⁴ to bear against the sleeve journal d⁵ threaded for adjustment in the receptacle. Check nut d⁶ is threaded to engage in sleeve journal. Engaging the shaft at one end is step screw d⁷ and carried at the other end is pulley d⁸ for connection with means for rotating it. Nipple d⁹ is connected with conduit B and nipple d¹⁰ is connected with conduit E.

Valve J is mounted on shaft d³ and has ports j arranged similarly to the ports in the valve seat.

I will describe the operation of my apparatus when used with a pressure tank and pressure pump, as the operation with a vacuum tank or a blower will be sufficiently clear from that description.

The pressure pump supplies the tank with air under pressure which is controlled by the safety valve f' and which is indicated by gage f. Air is conveyed from the tank to the receptacle by conduit E. Stop cock e being opened the desired pressure in the conduit will be obtained by adjustment of the needle valve and will be indicated by gage e'. Valve J is rotated through pulley d⁸ and is adjusted with reference to its valve seat by means of the step-screw and sleeve journal. The ports in the valve are arranged to register alternately with ports d' and ports d² of the valve seat. When the valve ports register with the ports d' impulses of pressure are conveyed to the body of the patient and when the valve ports register with ports d² of the valve seat pressure is exhausted to the atmosphere, and for each revolution of the valve as shown there will be six impulses and six exhausts with the result that the number of impulses of pressure per unit of time will be much greater than with any apparatus heretofore known, and this is due to my constantly rotating valve and to the arrangement of ports.

The advantage of my arrangement of stop-cock, gage and needle valve in conduit E is that the operator can regulate and observe the exact amount of pressure that is being transmitted to the patient and this pulsating

pressure can be maintained uniformly regardless of the pressure in the tank, the only requirement being that the pressure in the tank be greater than the desired pressure on the patient.

Any suitable number of ports in the valve and valve seat may be used, depending on the treatment desired.

It will be clear that when a vacuum is used that air is withdrawn through the ports d' and when ports d^2 are open that air is supplied from the atmosphere, and the rest of the operation when vacuum is used will be clear from the description already given. In some cases I substitute for the tank F a blower which will not depart from the principle of my invention, which is that a source of pressure may be connected with the body of the patient by a conduit which has means to alternately apply the pressure to, and relieve it from the body of the patient, to gain the advantages recognized to be due to the rapid application of pulsations of pressure to the body.

It will be clear that in the form of my invention herein shown tank F is the source of pressure, eye-cup A is the instrument for application to the body and that pipes B and E constitute a conduit connecting them, while the valve J is the means in that conduit for alternately connecting eye-cup A first with tank F and then with the atmosphere. It will also be clear that when operating under a vacuum the ports d^2 and pipe B constitute the conduit connecting eye-cup A with the source of pressure which in this case is the atmosphere and valve J will then alternately connect instrument A first with the relatively high pressure of the atmosphere and then with the relatively low pressure of the tank F.

What I claim is:

1. An apparatus of the character described comprising a source of constant pressure; an instrument for application to the body; a conduit connecting the source of constant pressure and the instrument; and means in said conduit to alternately connect said instrument first with the source of constant pressure and then with an atmosphere of lower pressure.

2. An apparatus of the character described

comprising a source of pressure; a three-way valve having the first port thereof connected with the source of pressure, the second port connected with the object to be operated upon, and the third port communicating with the atmosphere; and means to continuously operate the valve to alternately connect the second port with the first and third ports.

3. An apparatus of the character described comprising a source of pressure; a three-way valve having a port leading to the object to be operated upon, a set of ports communicating with the source of pressure and a set of ports communicating with the atmosphere; and means to continuously rotate the valve to alternately connect the first mentioned port first with one of the ports of the first set and then with one of the ports of the second set.

4. An apparatus of the character described comprising a source of pressure; a rotary three-way valve having a port leading to the object to be operated upon, a set of ports communicating with the source of pressure and a set of ports communicating with the atmosphere, and means to continuously rotate the valve to alternately connect the first mentioned port with the two sets of ports.

5. A three-way valve comprising a receptacle having two chambers; a valve seat separating the chambers and having one set of ports leading from one chamber to the other and having another set of ports leading from one chamber to the atmosphere; a valve to fit the valve seat and having ports to alternately register with the two sets of ports of the valve seat and means to rotate the valve.

6. The combination of a three-way valve; a source of constant pressure; a conduit connecting the source of constant pressure and three-way valve; a pressure gage for that conduit; a stop-cock in the conduit between the three-way valve and gage and a needle valve in the conduit between the gage and source of constant pressure for regulating the capacity of the conduit; substantially as, and for the purposes, described.

DANIEL C. FISHER.
